I. P. THUNELL.
CLOTHES AND HAT HANGER CABINET.
APPLICATION FILED JUNE 18, 1917.

1,278,790.

Patented Sept. 10, 1918.

INVENTOR:
Isaac P. Thunell,
By C. J. Belp.

Attorney.

UNITED STATES PATENT OFFICE

ISAAC P. THUNELL, OF SALT LAKE CITY, UTAH.

CLOTHES AND HAT HANGER CABINET.

1,278,790.

Specification of Letters Patent. Patented Sept. 10, 1918.

Application filed June 18, 1917. Serial No. 175,336.

To all whom it may concern:

Be it known that I, ISAAC P. THUNELL, a citizen of the United States, residing at Salt Lake City, in the county of Salt Lake 5 and State of Utah, have invented certain new and useful Improvements in Clothes and Hat Hanger Cabinets, of which the following is a specification.

This invention relates to clothes hangers, 10 and pertains especially to a combination of co-acting clothes hangers adapted to be contained within a wall cabinet in closed position, and to be projected from the cabinet when the latter is in open position.

15 The principal object of the invention is to provide a plurality of hangers, for various articles of wearing apparel, of such novel and peculiar construction and connection with a wall cabinet as to be contained 20 within the cabinet in closed position, and as to be projected from and suspended by the cabinet in open position.

A further object of the invention is to provide a cabinet with special devices for 25 holding hat and clothes hangers in compact position within the cabinet in closed position, and for suspending the hangers from the cabinet in open position.

A still further object of the invention is to 30 provide a cabinet with swinging arms of such character as to suspend clothes hangers, and to furnish special hat racks or hangers adapted to be hung from and suspended by said arms.

35 In the accompanying drawings forming part of this application:—

Figure 1 is a perspective view of a closed wall cabinet, embodying my invention.

Fig. 2 is a front view showing the cabinet 40 door open and containing the various racks and hangers.

Fig. 3 is a perspective view of an open cabinet showing the various racks and hangers as in position for use.

45 Fig. 4 is a detail perspective view of one of the standard racks partly broken away.

Fig. 5 is a similar view of one of the hanging racks.

50 Fig. 6 is a detail perspective view of one of the coat hangers, showing its hook member in folded position.

Fig. 7 is a detail perspective view of one of the cabinet brackets.

55 Fig. 8 is a detail perspective view of one of the arm hinges.

Fig. 9 is a perspective view of a modification.

The same reference characters denote the same parts throughout the several views of 60 the drawings.

In carrying out my invention I preferably employ an ordinary wall cabinet, and such cabinet is shown in the drawings for illustrating the application of my invention, but other similar cabinets of various size may 65 be used, or the invention may be applied to wall closets or wardrobes, with the same effect and results. The cabinet 1, which is shown secured to a wall, is of the usual or ordinary depth, and has a hinged door 2, 70 and a shelf 3, having a convexed concaved edge permitting the articles placed thereon and thereunder to be readily grasped for removal.

Referring now to the various improved 75 devices attached to and connected with the cabinet, each of such devices will be hereinafter particularly described in detail.

The back 1^a of the cabinet has transverse parallel slots 1^b, reinforced by metal plates 80 2^a, secured to the inner face of the said back and having a slot 3^a, corresponding with the slots 1^b, so that suitable screws 2^b, may be worked at various positions through 85 said slots for securely suspending the cabinet upon various walls in various positions, and in other places as may be found most suitable, convenient or desirable. While this means of fastening the cabinet is preferable 90 I do not confine myself thereto. But it is 95 obvious that, having the securing screws extend through the cabinet back affords substantial means for firmly anchoring the cabinet, and also affords means whereby the screws may be shifted to various positions 95 in the slots, for finding the most convenient and desirable place or position for driving the screws. The cabinet sides have vertical cleats 1^c, for holding certain hangers.

The inner face of the back of the cabinet 100 is provided with a pair of brackets comprising a flange 4 secured to the upper portion of said face by suitable screws, and an arm 5 projecting at right angles from the flange. These arms are shorter than the depth of 105 the cabinet, permitting the arms 7 to be folded against the end of the brackets, and the top edge of said arms is provided with a plurality of small notches 6, and a central large notch 6^a, the function or purpose of 110

these arms and their notches will hereinafter be fully explained.

The cabinet attachments for supporting a plurality of hat and coat hangers, comprise 5 a pair of upper swinging arms 7 and a like pair of lower arms 8, each of said arms being hinged or pivoted at 8^a near the front edge of each side of the cabinet by a hinge member 9 secured to the inner face of said 10 sides, and swingable inwardly in overlapped position within the cabinet and in front of the bracket arms 5. The arms 7 and 8 being swingable outwardly to any position desired. Said arms and the brackets are the 15 only actual attachments secured to the cabinet.

There are two kinds of hat racks or hangers, and a special coat or clothes hanger, embodied in my invention, all of which are 20 applied to the swinging arms 7 and 8. The coat hanger has a central thin portion 10, to which is pivoted at 11, the ends of a single piece of wire 12, which form a fork to straddle the portion 10, and permit the hook 13 25 formed by this wire to be folded in such position on the top edge of this hanger as to rest upon said edge for convenience in packing or storing these hangers on the cabinet shelf 3. This hook 13 fits the swinging arms 8 so 30 as to suspend these hangers in slidable position on said arms.

The hat racks or hangers 14 are slidably suspended by the swinging arms 7, and these racks being all of the same construction only 35 one of them will be described in detail. A single piece of wire is bent and folded upon itself to form upwardly curved hat-hanger members 15. The wire is extended vertically from a point central of the curved 40 members 15, so as to form a central double stem 16 and a spread hook 17 which fits the arms 7. The other form of hat rack or hanger comprises a single piece of wire, one end of which is bent to form a plurality of 45 parallel loops 18 fitting and slidable on the swinging arms 7. The wire is extended vertically from said hooks to form a standard 19, and the wire is branched laterally from the top of the standard 19, and folded upon 50 itself to form hat-hanging ends 20. The other end of this wire is projected centrally above the cross arms or racks 20, as a continuation of the said standards, and forms another means for hanging a hat, cap or the 55 like. Obviously the intersection of the cross arms and the vertical portions of all these wire racks or hangers may be soldered, or

tied with fine wire 21, as shown, and certain of the hat hangers are reinforced by suitable wire 22.

Referring to the modification shown in Fig. 9 of the drawings, the slotted back plate 25, and the side or hinge member 26, are made in one piece, and the hanger arm 27, is hinged at 28 to the side member 26.

In storing the various articles, hereinbefore described, in the cabinet, as shown in Fig. 2 of the drawings, the hooks of the coat or clothes hangers are folded as in Fig. 6 of the drawings, and nested upon the shelf back 70 of the cleats 1^c, the hanging hat racks are hooked into the small notches of the bracket-arms so as to depend therefrom, the standard hat hangers are laid lengthwise in the central or large notch of the bracket arms, and 75 the swinging arms are closed in pairs one upon the other against the notched arms for retaining said racks, so as to permit the cabinet door to be closed without interference.

Obviously one or more swinging arms may 80 be attached to the cabinet, and the garment hangers and hat racks may be multiplied as desired or as occasion may demand.

Although I have illustrated the attachments as applied to a wall cabinet, they may 85 be applied to a wall closet, wardrobe or other similar inclosure, for the same purpose.

I do not wish to be understood as confining my invention to any particular size, 90 number of parts, or material, but reserve the right to make such changes and variations therein and in the manufacture and application of the several parts, as may come within the scope of the appended claim.

Having thus described my invention what 95 I claim as new and desire to secure by Letters Patent is:—

In a clothes hanging wall cabinet, a pair of hanger brackets having one end secured to the inner face of the back of the cabinet 100 and terminating within the cabinet, a plurality of hanger-supporting arms, means for hinging the arms to the inner face of the sides of the cabinet to afford free swinging movement outside of the cabinet, said arms 105 adapted to overlap in pairs with one pair against the front end of said brackets in closed position of the cabinet.

In witness whereof I hereunto set my hand in the presence of two witnesses.

ISAAC P. THUNELL.

Witnesses:

OSCAR OLSON,
N. P. CHRISTENSEN.
